(57) **CLAIM**

We claim the ornamental design for a hybrid transaction device, as shown and described.

DESCRIPTION

FIG. 1 depicts a perspective view of the front face of a hybrid transaction device.

FIG. 2 depicts a perspective view of the rear face thereof.

FIG. 3 depicts a front elevational view thereof.

FIG. 4 depicts a back elevational view thereof.

FIG. 5 depicts a side elevational view thereof.

FIG. 6 depicts an opposite side elevational view thereof.

FIG. 7 depicts a bottom plan view thereof.

FIG. 8 depicts a top plan view thereof.

FIG. 9 depicts a cross-sectional view thereof.

FIG. 10 depicts a perspective view of the front face of a second embodiment of a hybrid transaction device.

FIG. 11 depicts a perspective view of the rear face thereof.

FIG. 12 depicts a front elevational view thereof.

FIG. 13 depicts a back elevational view thereof.

FIG. 14 depicts a side elevational view thereof.

FIG. 15 depicts an opposite side elevational view thereof.

FIG. 16 depicts a bottom plan view thereof.

FIG. 17 depicts a top plan view thereof; and,

FIG. 18 depicts a cross-sectional view thereof.

The broken lines in the drawings illustrate environmental structure on the article and form no part of the claimed design.
